UNITED STATES PATENT OFFICE.

WILLIAM PERCY ALLEN, OF BRIDGEPORT, CONNECTICUT.

DESIGN FOR AN EYE FOR CORSET-HOOKS.

SPECIFICATION forming part of Design No. 31,176, dated July 11, 1899.

Application filed May 7, 1897. Serial No. 635,593. Term of patent 14 years.

To all whom it may concern:

Be it known that I, WILLIAM PERCY ALLEN, a citizen of the United States, residing at Bridgeport, Fairfield county, State of Connecticut, have invented and produced a new and useful Design for Eyes for Corset-Hooks, of which the following is a specification.

The leading feature of my design consists in an eye for corset-hooks the exterior contour of which is U-shaped and the interior contour comprises a slot having parallel sides opening into an enlarged slot having curved sides, the ends merging into the rounded ends of the hook. Thus, referring to the accompanying drawing, the eye A has a U-shaped exterior contour α , merging into the rounded

ends α' , and the interior contour is in the form of a slot α^2 , having parallel sides opening into the enlarged slot α^3 , the sides of which are reversely curved and which merge into the rounded ends α' . In the ends are openings b .

What I claim is—

The design for an eye for corset-hooks, substantially as shown and described.

In testimony whereof I have signed my name to this specification in the presence of two subscribing witnesses.

W. PERCY ALLEN.
